[57] CLAIM

The ornamental design for a case for keeping face-sebum absorbing paper, as shown and described.

DESCRIPTION

FIG. 1 is a perspective view of a case for keeping face-sebum absorbing paper showing our new design in a closed or folded state;

FIG. 2 is a front elevational view thereof;

FIG. 3 is a rear elevational view thereof;

FIG. 4 is a top plan view thereof, with a bottom plan view being a mirror image;

FIG. 5 is a left-hand side elevational view thereof, with a right-hand side elevational view being a mirror image;

FIG. 6 is a perspective view of the case for keeping face-sebum absorbing paper shown in a opened or unfolded state;

FIG. 7 is a top plan view thereof;

FIG. 8 is a bottom plan view thereof;

FIG. 9 is a left-hand side elevational view thereof, with the right-hand side elevational view being a mirror image;

FIG. 10 is a front elevational view thereof; and,

FIG. 11 is a rear elevational view thereof.
